Application September 9, 1942, Serial No. 457,712

2 Claims. (Cl. 280—11.13)

Granted under the act of March 3, 1883, as amended April 30, 1928; 370 O. G. 757)

This invention described herein, if patented, may be manufactured and used by or for the Government for governmental purposes, without the payment to us of any royalty thereon.

The present invention relates to skis. More specifically, it relates to an improved means for securing a ski climber or "skin" to the sole of a ski.

It is recognized that in the past numerous different arrangements have been resorted to in order to secure a ski skin to the sole of the ski, but it is submitted that the present disclosure provides a more useful and more satisfactory device than those heretofore devised, particularly in that the present invention provides a stronger and simpler rear fastening than those of prior art devices, and one that may be attached to and released from the ski more easily.

In the drawing of the present specification,

Fig. 1 is a side elevational view of a ski with a climber attached according to the teachings of this invention;

Fig. 2 is a plan view of the climber alone;

Fig. 3 is a detail sectional view of the forward end of a ski, with the climber attached;

Fig. 4 is a detail sectional view of the rear end of a ski, with the climber attached;

Fig. 5 is a detail sectional view taken on the plane of the line 5—5 of Fig. 4, and

Fig. 6 is a perspective view of an intermediate portion of the climber, showing one of the retaining straps.

The ski climber of the present invention consists, in general, of a long narrow strip of fabric 11 secured to the sole of a ski 12, and having a long nap on its lower surface, the nap being directed toward the rear end of the ski, so that it will permit free forward movement of the ski but will resist any rearward movement.

The forward end of the climber 11 is provided with a web loop 14 which encircles the point of the ski, and carries an adjustable buckle 15. The loop and buckle serve as the front fastening means for the climber, the forward end of which is provided with a web strap 16 which engages the buckle and permits the fabric 11 to be tensioned between the forward fastening loop 14 and a rear fastening device to be hereinafter described.

The fabric is also provided with intermediate fastening means consisting of fabric reinforcements 17 stitched to the fabric 11 at spaced areas 18 to provide a transverse channel through which the strap 19 passes. The strap 19 encircles the ski as shown in Fig. 1, to secure the fabric against

lateral movement with respect to the ski and yet permit longitudinal movement.

The rear end of the climber 11 is reinforced by a fabric layer 21, and a rather wide web strap 22 is stitched between the fabric 11 and the reinforcement 21. The strap 22 is looped around one of the straight portions of a triangular link 23, which serves as a stress distributing member to unite the rear end of the climber to the short anchor chain 24, so that it may be firmly secured to the rear portion of the ski. The chain 24 lies in a longitudinal groove 25 in the sole of the ski, and extends through a hole 26, so that the end of the chain may be anchored by a cross link 27. As shown in Fig. 5, the cross link 27 is formed to include one straight side 28, and a crimped side 29 arranged to seat in the hole 26 and to provide an internal notch in which the last link of the chain 24 will seat.

The arrangement is such that when the parts are in the position illustrated in Figs. 4 and 5 of the drawing the cross link 23 will anchor the chain 24, link 23, strap 22, and rear end of the fabric 11 firmly to the sole of the ski; the stress on the fabric being well distributed across its width by the triangular link 23 and the fabric reinforcement 21. The climber may be easily released from the ski, however, by simply lifting the cross link 27, and passing it endwise through the hole 26.

From the foregoing, it will be apparent that the present invention provides a simple, novel, and rugged ski climber fastening having obvious advantages in simplicity and ease of operation. It is believed, however, that while the present preferred construction, as illustrated in the drawing, is the most satisfactory for the purpose, yet certain minor modifications may be made without departing from the teachings of this application, and it is therefore believed that the scope of the present invention should be regarded as limited only by the terms of the appended claims.

Having thus described our invention, what we claim as new and desire to secure by Letters Patent is:

1. In combination, a ski including a longitudinal groove on its lower surface, and a vertical hole extending through the ski adjacent the rear end thereof; together with a fabric climber having forward fastening means, intermediate fastening means, and rear fastening means; the forward fastening means comprising a loop encircling the point of the ski with a strap and buckle to secure the loop to the forward end of the climber; the intermediate fastening means

consisting of fabric reinforcements stitched to the climber at spaced areas to provide a transverse strap channel, a strap passing through said channel and encircling the ski, and a buckle to secure the strap; the rear fastening means including a chain secured to the rear of said climber and extending longitudinally of the ski and through the aforementioned vertical hole through the ski; and a cross link adapted on the top surface of the ski to anchor the end of the chain.

2. In combination, a ski including a longitudinal groove on its lower surface, and a vertical hole extending through the ski adjacent the rear end thereof and intersecting said longitudinal groove; together with a fabric climber having forward fastening means, intermediate fastening means, and rear fastening means; the forward fastening means comprising a loop encircling the point of the ski with a strap and buckle to secure the loop to the forward end of

the climber; the intermediate fastening means consisting of fabric reinforcements stitched to the climber at spaced areas to provide a transverse strap channel, a strap passing through said channel and encircling the ski, and a buckle to secure the strap; the rear fastening means consisting of a fabric reinforcement and a wide strap secured to the rear end of the climber, a triangular link, a loop in the strap encircling a transverse straight side of the triangular link, a chain secured to the rear point of said triangular link and extending longitudinally of the ski in the aforementioned longitudinal groove and through the aforementioned vertical hole through the ski; and a cross link on the end of the chain, the cross link including one straight side and a crimped side adapted to seat in the opening through the ski and provide a notch to receive and anchor the end link of the chain.

BESTOR ROBINSON.

WALLACE E. BREUNER.
